UNITED STATES PATENT OFFICE.

ORLA J. SCOTT, OF CHICAGO, ILLINOIS.

BOILER-FEEDER.

SPECIFICATION forming part of Letters Patent No. 618,484, dated January 31, 1899.

Application filed August 19, 1897. Serial No. 648,806. (No model.)

To all whom it may concern:

Be it known that I, ORLA J. SCOTT, a citizen of the United States, residing at Chicago, in the county of Cook, State of Illinois, have 5 invented certain new and useful Improvements in Boiler-Feeders; and I hereby declare the following to be a full, clear, and exact description of the same, reference being had to the accompanying drawings, in which—
10 Figure 1 is a view in side elevation of a boiler (which may be one of a series) and a feed-water system connected therewith and embodying my invention, parts being broken away to show the interior of the primary receivers, &c. Fig. 2 is an enlarged sectional view of the differential valve which is interposed between the steam-supply and the primary receiver and connected with the main receiver, so as to be controlled by the pressure 15 in the main receiver. Fig. 3 is an enlarged sectional view of the graduating steam-admission valve which is interposed between the differential valve and the primary receiver. Fig. 4 is an enlarged sectional view 20 of the upper or steam-induction end of the primary receiver, the perforated-cone jet-spreader being shown in full line. Fig. 5 is an enlarged sectional view of the steam-inlet valve to the main receiver. Fig. 6 is an enlarged 25 sectional view of a float-controlled relief-valve for unbalancing the steam-inlet or induction valve of the main receiver when the water in the feed-pipe falls below a given level. (To show the relation thereof, Figs. 5 and 6 have been coupled by a pipe shown in dotted lines.) Fig. 7 is an enlarged sectional 30 view of one of the feed-water-admission valves which controls the flow of the feed-water to an individual boiler. Fig. 8 is an enlarged 35 view, partly in section, of a float-controlled auxiliary valve for causing the fall of the boiler-water below a given level to open the feed-water-admission valve. (To indicate the relation of the valves shown in Figs. 7 and 8, they have been connected up by a pipe shown in dotted lines.) Figs. 9, 10, 11, and 12 are 40 detail and sectional views of portions of the auxiliary valve shown in Fig. 8.

Like symbols refer to like parts wherever 45 they occur.

My present invention relates to certain im-

provements in the receivers and valves of automatic boiler-feeders in general, and though said improvements have been especially devised with reference to the operation 55 of that system of boiler-feeders wherein are combined a primary receiver, a main receiver, a steam-supply, and a differential valve interposed between the steam-supply and the primary receiver and controlled by the pressure 60 in the main receiver, as set forth in and covered by my Letters Patent Nos. 577,325 and 577,392, dated February 16, 1897, yet it is not my intention to limit my present claims to the individual constructions or to confine 65 them to the particular combinations chosen for purposes of illustration.

One object of my invention is to quicken the operation of the primary receiver, reduce the agitation of the receiver-water to a minimum, and avoid the loss of force incident to the rapid condensation of the steam when first admitted to the receiver, and this I accomplish by providing the receiver with a funnel-shaped or coniform dome or steam-induction 70 passage, whose greatest diameter is about half the diameter of the body of the receiver and whose length is such as to permit the expansion of the steam and reduction of the jet force before any extended surface of water is 75 presented to the incoming steam, and such a construction or its equivalent embodies one feature of my invention.

In conjunction with a receiver having a funnel-shaped or coniform steam-induction 80 passage and as an auxiliary thereto in disseminating the steam and avoiding agitation of the receiver-water I provide said coniform steam-induction passage at its least diameter or jet-inlet with a coniform screen or perforated metal plate, and such a construction or 85 its equivalent embodies a second feature of my invention.

Another object which I have in view in the present invention is such a construction of the 90 "differential" valve of the system as shall prevent the accumulation of foreign matter on the valve, and thus insure its effectiveness, and this I accomplish by combining with the valve a cup for the reception of water of condensation, (or oil, as the case may be,) which 95 fluid is alternately transferred from valve to

cup, thus freeing the valve from any foreign matter, and such a construction or its equivalent embodies a third feature of my invention.

In order to determine at all times whether 5 the differential valve is operating effectively, I combine therewith a rod or stem which projects through the valve-casing and which may be inclosed by a screw cap or cup or equivalent means of preventing any leakage, and 10 such a construction or its equivalent embodies a fourth feature of my invention.

A further object of my present invention is to graduate the admission of steam to the primary receiver without obstructing or limiting the exhaust therefrom, and this I accomplish by means of a spring-seated valve having an adjustable independent stem for holding the valve off its seat, which or its equivalent, in combination with the receiver 15 and its steam induction and eduction pipe, embodies a fifth feature of my invention.

In order to control the admission of steam to the main receiver by the fall of water therein or in the eduction-pipe thereof, I combine 20 with the steam-induction pipe of the main receiver a steam-seated valve and a relief-valve which controls the exhaust of the steam-seated valve and is in turn controlled by a float arranged in the main receiver or eduction-pipe leading therefrom, and such a combination or its equivalent embodies a sixth feature of my invention.

In order to regulate the admission of the feed-water to a boiler or to any boiler of a 35 battery, I arrange in the feed-water pipe, be the same a main or a branch pipe, and preferably adjacent to the boiler supplied by said pipe, a feed-water-admission valve connected with the steam-space of the boiler, said connection being provided with an auxiliary 40 valve actuated by the rise and fall of the boiler-water through the medium of a float or otherwise, and such a combination or its equivalent embodies a seventh feature of my 45 invention.

There are other minor features of invention, some involving particular combinations and others dependent on particular constructions of the individual elements of given combinations, all as will hereinafter more fully appear.

I will now proceed to describe my invention more fully, so that others skilled in the art to which it appertains may apply the 55 same.

In the drawings, B indicates a boiler, (or one boiler of a series;) a, the mud-drum; b, the steam-dome, and c the water-column thereof, with which the boiler-feeder system is combined.

The system as chosen for purposes of illustration comprises a primary receiver P, connected with the steam-space of boiler B or other source of steam-supply by suitable tubing, a differential valve D, interposed between the boiler B and the primary receiver P, and a main receiver M, having an air-cock m

and connected up by suitably-valved tubing or piping with the boiler B or other source of steam-supply and with the primary receiver 70 P and also connected with the differential valve D, which is interposed between the boiler or steam-supply and the primary receiver.

1 indicates a steam-pipe leading from the 75 dome or steam-space of boiler B and which divides into branches 2 and 3, the first of which, 2, leads to the primary receiver P and the second, 3, to the main receiver M. Arranged in the steam-pipe 1 is a globe or other 80 suitable valve 1^a, by means of which the steam may be cut off from the feed-water system.

Arranged in the branch steam-pipe 2, which leads to the primary receiver P, is a differential valve D, connected with the main receiver M by an equalizer-pipe 4, and between the differential valve and the primary receiver is a graduating-valve G. This differential valve (see Fig. 2 for details of construction) is in direct connection with the boiler or 90 source of steam and with the primary receiver and is in effect both an induction and exhaust valve for the primary receiver, for which purpose the casing is divided diagonally by the partition d¹, having the steam-port 95 therein, and transversely by the partition d², having the exhaust-port therein, which ports are controlled by piston-valves d³ and d⁴. The steam-valve d³ constitutes a portion of the differential piston D³, arranged in the cylinder-chamber D², from which chamber the equalizer-pipe 4 leads to the main receiver, whereby the throw of the differential valve is controlled by the pressure in the main receiver M. The exhaust-valve d⁴ moves in a 100 guide-cylinder or annular shell constituting a chamber D⁴, around which the exhaust-channel d⁵ passes to the exhaust-pipe d⁶ and from which chamber D⁴ one passage d⁷ leads to a suitable cup D⁵, (see Fig. 1,) while a second passage d⁸ (which may be closed by a suitable plug) provides for the withdrawal of any 105 contained or deposited fluid and sediment.

The chamber D⁴ and cup D⁵ are a provision for retaining in the valve water of condensation (or oil) for clearing the valve from any foreign matter which might otherwise deposit therein and interfere with the proper working of the valve, and said contained fluid is alternately drawn into and forced from chamber 115 D⁴ by the movement of piston-valve d⁴. In order to ascertain at any time the position of the differential valve, I provide the differential piston D³ with a small stem d⁹, which projects through the casing of the valve and may, 120 if desired, be inclosed by a screw-cap d¹⁰ to prevent leakage. By this means the valve 125 may also be worked to displace any foreign matter which may accumulate on the valve.

The graduating-valve G, which is interposed 130 between the differential valve D and the primary receiver P, (for details of construction see enlarged Fig. 3,) is one in which the valve is so arranged and constructed as to be nor-

5 mally closed by the steam-pressure from the boiler, though free to open fully when the steam-pressure is removed, and is held open or off its seat the desired distance for the admission of steam and against the steam-pressure by mechanical means. The preferred construction is that shown in the drawings, wherein the casing is divided by a partition 10 g' , in which is the steam-port g^2 , provided with the spring-pressed valve g^3 , whose stem g^4 moves in suitable guides and is engaged by the independent threaded stem G' , by means of which the valve g^3 may be forced and held off its seat to any desired distance to admit 15 live steam to the primary receiver P and at the same time open freely in reverse direction to permit the escape of the exhaust from said primary receiver.

20 The branch steam-pipe 2 leads from the graduating-valve G to the primary receiver P .

Feed-water receivers from which the feed-water is discharged by steam-pressure are commonly so constructed as to present an extended water-surface to the steam-jet at the 25 instant the jet is admitted and before the water has fallen sufficiently to permit the expansion and diffusion of the steam, and as a consequence the receiver-water is agitated and the steam rapidly condensed, with resultant 30 loss of force, heating of the water, and delay in the operation of the devices. To overcome these objectionable features, I provide the receiver P , which is usually of cylindrical form, with a conical dome p' or steam-induction 35 passage, whose greatest diameter is preferably about half the diameter of the body of the receiver (more or less) and whose length is sufficient to allow of such expansion of the steam as will check its velocity before it comes in 40 contact with any extended surface of water, and as a means of breaking up and disseminating the jet of steam I cover the delivery end of branch pipe 2 within the primary receiver P with a conical screen p^2 , though said 45 screen may be omitted, if desired.

The primary receiver P is directly connected up with the usual feed-water-supply pipe S , which is provided with a swinging check-valve s or other suitable means of preventing the return flow of the feed-water. From the primary receiver P said supply-pipe S passes to the main receiver M , between which and the primary receiver it is provided with a check-valve s' and, if desired, at its 55 lowest point with a drain-plug s^2 .

5 M indicates the main receiver, which is supplied with steam through the branch steam-pipe 3, in which is arranged the steam-induction valve H , the operation of which is controlled by relief-valve I. This steam-induction valve H for the main receiver is composed of a disk valve h' , (see enlarged detail section Fig. 5,) which controls the port leading to the main receiver M , and through steam branch 65 pipe 3 is in direct communication with the boiler or other source of steam-supply.

The stem h^2 of disk valve h' passes steam-

7 tight from the lower or disk chamber through the casing and into a superposed cylinder h^3 , where it is provided with a piston h^4 , the stem h^2 being provided with a steam-passage h^5 , whereby and by means of a port h^6 steam is admitted into the cylinder h^3 over the piston h^4 . A small port h^7 also admits steam from passage h^5 to the opposite or under side of piston h^4 , and between said surface of the piston and the bottom of cylinder h^3 is interposed a spring h^8 , which operates to lift the piston, and with it the disk valve h' , after the pressure has equalized on both heads of piston h^4 and 80 at such time as the pressure in main receiver M has approximated the boiler-pressure.

85 From the underside of piston h^4 an exhaust-port h^9 delivers into an exhaust-pipe 5, which leads to the relief-valve I.

I indicates a relief-valve so located as to be operated by the descent of the feed-water in the main receiver M or in the upper end of the supply-pipe S , which pipe is the feed-water eduction as well as induction pipe of 90 the main receiver. By preference said relief-valve I is located in an enlargement of the feed-water and supply pipe just below the main reservoir M , (see Fig. 1,) which enlargement (or water-column) may be provided with 95 a gage-glass, and the main reservoir is itself preferably located above the desired water-level of the boiler, as indicated in Fig. 1 of the drawings.

The casing of relief-valve I (for detail of 100 construction see Fig. 6) is provided with a port i' , with which the pipe 5, leading from the exhaust-port h^9 of valve H , connects, said port or passage i' delivering into valve-chamber i^2 , from which an exhaust-port i^3 discharges 105 through exhaust-pipe 6. Journaled in the valve-casing is a short shaft i^4 , provided with an arm i^5 , which carries or operates a slide-valve i^6 , which slide controls the exhaust-port i^3 , the opposite end of said short shaft i^4 being 110 connected to a float I' , arranged in the water-column of the supply and feed pipe, so that the relief-valve or slide-valve i^6 is moved by the rise and fall of the water in the supply-pipe S . Within the column may be placed 115 pins or stops i^7 (see Fig. 1) to limit the movement of the float I' and the valve i^6 , operated thereby.

7 indicates the main feed-water pipe, which 120 branches from the supply-pipe S just below the main receiver M and enlargement or float-chamber last noted, and said feed-pipe 7 is provided with a swinging check-valve s^3 or other suitable means of preventing the backflow of the feed-water. Between said 125 check-valve s^3 and the boiler, so as to be operated by the back pressure in the feed-pipe, is a spray-pipe 8, provided with a suitable valve 8^a , which pipe delivers into the upper end of main reservoir M , and, if desired, 130 the reservoir end of said spray-pipe may be provided with a disk 8^b to break up or nebulize the water-jet as it is delivered into the upper part of the main reservoir.

From the main feed-pipe 7 separate branch feed-pipes 9 lead to the respective boilers of the series, provided there be a battery of boilers, and in each branch leading to a boiler 5 I locate a feed-water-admission valve K. The branch feed-pipe 9 may be provided with a suitable gate-valve s^4 between the feed-water-admission valve and the boiler, and said feed-pipe, by preference, is arranged to 10 deliver into the mud-drum. The admission-valve should be of a character to be operated by steam-pressure in the boiler and is preferably one (see Fig. 7 for details of construction) wherein the casing is divided by a transverse partition k^4 , provided with a valve-port k^2 , having a suitable disk or piston valve k^3 for closing the port.

The stem k^4 of the valve k^3 may be provided with suitable wings or guide-lugs k^5 20 for centering and guiding the valve and terminates in a piston k^6 , fitted into a suitable cylinder k^7 , connected to or forming part of the valve-casing. The piston k^6 is preferably a hollow or cup piston containing a 25 spring k^8 , which under certain conditions assists in opening the valve. The cylinder k^7 back of the piston k^6 is provided with a port k^9 , by means of which and a suitable pipe 10 connection is made between said cylinder and 30 auxiliary valve L.

The area of valve k^3 and piston k^6 and the power of spring k^8 are so proportioned that the valve k^3 will be normally closed by the pressure of water in the feed-pipe, but will 35 open when steam from the boiler enters the cylinder k^7 back of piston k^6 .

L indicates an auxiliary valve for controlling the admission to an exhaust of steam from cylinder k^7 of feed-water-admission 40 valve K, with which it is connected by pipe 10.

The auxiliary valve L (for detail of construction see Figs. 8, 9, 10, 11, and 12) is one which is controlled by the rise and fall of the boiler-water by means of a float or in other 45 suitable manner. Preferably it is connected with a water-column c, (which may be provided with a glass gage,) which column contains the float and levers that actuate the valve. The valve-casing may consist of a 50 plug l^1 , provided with the coupling l^2 , by which it connects with pipe 10 and valve K and from which a steam port or passage l^3 leads to the slide-valve, a coupling l^4 , to which is connected the exhaust-pipe and to which 55 an exhaust-steam port or passage l^5 leads from the valve, and a coupling l^6 for the attachment of a whistle W and to which a steam-port l^7 leads from the slide-valve. L', Fig. 10, shows the valve-seat and the relative position of the ports l^3 , l^5 , and l^7 , and on said 60 valve-seat is arranged the slide-valve L^2 between the bracket posts or pillars l^8 l^9 , the valve L^2 being held against its seat by a suitable spring l^{10} and operated by the short arm of lever L^3 , which is pivoted on the bracket-posts l^8 l^9 and to the long arm of which the float L^4 is connected.

The slide-valve L^2 is provided with a passage l^0 (see Fig. 12) by which the port or passage l^3 and the exhaust port or passage l^5 are 70 disconnected when the boiler-water is at the desired level, a second port l^{10} , which registers with the port or passage l^7 , leading to the whistle at such times as the boiler-water falls below the normal level, and the slide-valve is 75 also cut away at l^{11} or otherwise formed to open the steam-passage l^3 , leading to the cylinder k^7 of the admission-valve K, whenever the boiler-water falls below the normal level. If the admission-valve K should fail to close 80 and the water in the boiler rise above the normal level, the continued rise of float L^4 would depress slide-valve L^2 until its upper edge would sink below port or passage l^7 leading to the whistle w , and a high-water alarm would 85 then be sounded.

The construction of my improved feed-water devices being substantially such as hereinbefore pointed out, their operation will be as follows: Supposing the main receiver M to be 90 empty and the primary receiver P filled with water by gravity or otherwise, the float I', which controls the relief-valve I, will be in its lowest position (see Fig. 1) and the little slide-valve i^6 (see Fig. 6) will be so placed as to 95 leave exhaust-port i^3 open, and this through-pipe 5 will leave open the exhaust-port h^9 (see Fig. 5) on the under side of piston h^4 of steam-induction valve II. Now on opening the globe-valve 1^a steam passes through pipes 2 and 3 to 100 the graduating-valve G, (see Figs. 1 and 3,) which is closed, and also into the steam-inlet valve II (see Figs. 1 and 2) of the main receiver M, and thence into said main receiver, as the disk h' is at this time (the exhaust- 105 back of piston h^4 being open) held off its seat by spring h^8 . The steam which enters the main receiver M finding no escape there is a rapid rise in pressure in the valve-casing, which, acting through ports h^2 and h^6 on the 110 upper surface of piston h^4 , overcomes spring h^8 and forces the disk h' on its seat, thus cutting off the steam from the main receiver M. At this point the air-cock m is opened, which permits the escape of the air and steam from 115 the receiver, and the graduating-valve G is also opened the required distance to admit of the desired steam-pressure in primary receiver P, whereupon the water is forced from primary receiver P up into the main receiver 120 M. The air-cock m having been closed to prevent the escape of water, the pressure rapidly rises in main receiver M and all its connections until the pressure on the under side of disk valve h' , aided by spring h^8 , overcomes 125 the pressure above the disk valve, and said valve is thrown open and steam from the boiler is again admitted to main receiver M. As the water rises in the receiver the float I' rises, closing the slide-valve i^6 and the exhaust h^9 from 130 beneath the piston h^4 , thus assisting in the opening of valve h' . At the same time the disk valve h' opens to admit steam to the main receiver the pressure in the main receiver, acting

through pipe 4 on piston D³ (see Fig. 4) of differential valve D, closes valve d³ and opens valve d⁴, thus cutting off the steam from and opening the exhaust to primary receiver P, whereupon primary receiver P immediately refills with water. The opening of disk valve h' and the admission of steam to main receiver M, as before specified, causes the feed-water to pass from the main receiver into main feed-pipe 7 past the swinging check-valves s³, which prevents its return, and onto the branch feed-pipes leading to the boilers to be supplied. The water continues to leave the receiver M until its surface is at a level slightly below the point in the feed (or supply) pipe where it will support the float I', whereupon the float I' drops, withdrawing the valve i⁶, and opening exhaust-port i³, permitting the escape of steam from the under side of piston h⁴, whereupon the valve h' is again closed by the pressure above it, and the steam is again cut off from main receiver M. Condensation of the steam confined in main receiver M then commences, and the back pressure in the main feed-pipe 7 forces a water-jet through pipe 8 into the upper part of main receiver M, which hastens the condensation and fall of pressure in the main receiver. The reduction of pressure in the main receiver, acting through pipe 4 on the piston D³ of the differential valve, opens the steam-inlet valve d³ and closes the exhaust-valve d⁴, thus again admitting steam to the primary receiver P, whereupon the several operations hereinbefore recited are repeated in succession until the boiler-water has reached the normal level, when the operation of the devices cease until such time as the boiler-water again falls below the normal level. When the boiler-water falls below the normal level, the descent of float L⁴ in column c, acting through lever L³ on slide valve L², (see Fig. 8,) causes the slide to rise and port l¹⁰ of the slide to register with the port l', leading to the whistle W, and an alarm is sounded. The same movement of slide L² also opens the passage or port l³, admitting steam, thence through pipe 10 behind piston k⁶ (see Fig. 7) of the admission-valve K unbalancing the valve k³, which is then thrown by spring k⁸ and permits the feed-water to enter the boiler. When the boiler-water again reaches the normal level, the rise of the float shifts the slide-valve L² down until the port or passage l⁹ thereof connects the passage l⁸, leading from behind piston k⁶, with the exhaust-passage l⁵, whereupon the admission-valve k³ will be closed by the pressure in the feed-water pipe. If, however, the valve k³ should fail to close, the continued rise of the water in the boiler and of the float L⁴ would still further depress the slide L² until the upper edge thereof would fall below and unclog port l', leading to whistle W, and a high-water alarm would be at once sounded.

Having thus described my invention, what

I claim, and desire to secure by Letters Patent, is—

1. In a feed-water apparatus, the combination with a feed-water-supply pipe and a steam-induction pipe, of a feed-water receiver having a steam-induction passage of truncated cone shape the maximum diameter whereof is less than that of said receiver, substantially as and for the purposes specified. 75

2. In a feed-water apparatus, the combination with a feed-water-supply pipe and a steam-induction pipe, of a feed-water receiver having a funnel-shaped or coniform dome or steam-induction passage, and a coniform strainer arranged over the steam-inlet; substantially as and for the purposes specified. 80

3. In a feed-water apparatus the combination with a feed-water receiver and its steam-induction pipe, of a spring-retained inlet-valve normally open, and means for automatically actuating said valve in the reverse direction by steam-pressure, substantially as and for the purposes specified. 85

4. In a feed-water apparatus the combination with a feed-water receiver its steam and feed-water-supply pipes, of a spring-retained inlet-valve normally open for admitting pressure to said receiver, a steam-cylinder containing a piston for actuating said valve to seat it, and means for controlling the exhaust-port of the cylinder by the rise or fall of the feed-water, substantially as and for the purposes specified. 90

5. In a feed-water apparatus the combination with a feed-water receiver its steam and feed-water-supply pipes, of a spring-retained inlet-valve normally open for admitting pressure to said receiver, a steam-cylinder containing a piston for actuating said valve to seat it, valve mechanism for controlling an exhaust-port in the cylinder, and a float actuated by the rise or fall of the feed-water for controlling said valve mechanism, substantially as and for the purposes specified. 100

6. The combination in a steam-inlet valve for feed-water systems, of a disk valve for controlling the steam-inlet port, a valve-stem therefor having a steam-passage and provided with a piston, a cylinder for the piston of the valve-stem, a spring which acts upon the piston of the valve-stem to unseat the valve, and means for opening and closing the exhaust-port of the piston-cylinder; substantially as and for the purposes specified. 110

7. In a feed-water system the combination with a feed-water receiver its steam-inlet and water-supply pipes, of a spring-retained inlet-valve normally open for admitting pressure to said receiver, and relief mechanism for controlling the exhaust-port of the steam-inlet valve, said relief mechanism comprising a slide-valve, a shaft for actuating the latter, and a float arranged in the feed-water-supply pipe for rocking said shaft, substantially as and for the purposes specified. 125

8. In a feed-water apparatus, the combina-

- tion with a primary receiver, and a main receiver, and suitable steam and water pipe connections, of a differential valve interposed between the steam-supply and the primary receiver and connected with the main receiver, and a graduating-valve interposed between the differential valve and the primary receiver, and so constructed that the flow of fluid may be positively restricted in one direction and unrestricted in the reverse, substantially as and for the purposes specified.
9. In a differential valve for feed-water apparatus, the combination with the exhaust-valve thereof, of a cylinder or guide-shell wherein the exhaust-valve moves, and a cup arranged upon the valve and communicating with the cylinder or chamber formed by the guide-shell of the exhaust-valve, substantially as and for the purposes specified.
10. In a differential valve for feed-water apparatus, the combination with the steam-inlet valve and its stem, of the steam-exhaust valve d^4 , the cylinder D^4 traversed by the valve d^1 said cylinder having a port, and a cup D^5 ; substantially as and for the purposes specified.
11. In a feed-water apparatus, the combination with a water-column or float-chamber having a neck adapted to receive a plug-casing, of a plug-casing in screw connection with

said neck provided with inlet and outlet steam-ports and a valve-seat, a valve having a passage or port for connecting said steam-port and outlet-ports, and means for connecting the valve with the float of the water-column, substantially as and for the purposes specified.

12. An auxiliary valve for feed-water apparatus, said valve having a plug-casing l' provided with ports l^3 l^5 and l^7 , and a slide-valve L^2 provided with ports l^9 and l^{10} , in combination with an alarm-whistle, and a feed-water-admission valve, actuated from said auxiliary valve; substantially as and for the purposes specified.

13. An auxiliary valve having a plug-casing l' provided with ports l^3 l^5 and l^7 , and a slide-valve provided with ports l^9 and l^{10} and a notch l^{11} , in combination with a feed-water-admission valve and a signal operated from said auxiliary valve; substantially as and for the purposes specified.

In testimony whereof I affix my signature, in presence of two witnesses, this 12th day of August, 1897.

O. J. SCOTT.
